CORD LOCK DEVICE FOR VENETIAN BLINDS

Edward E. Schaefer, Oak Park, Ill.

Application June 24, 1943, Serial No. 492,030

6 Claims. (Cl. 160—173)

This invention relates to Venetian blinds, and more particularly to an improved cord lock mechanism adapted to secure the raising and lowering cords of the blind in adjusted vertical position and a novel cord arrangement embodying said improved cord lock mechanism. The present invention has particular application to large commercial blinds which are in use, for instance, on large bank and store windows.

Heretofore, the Venetian blinds which have been applied to the large, wide windows of banks, stores, etc., have possessed inherent disadvantages arising from their large size which disadvantages have limited their commercial adaptation. Because of the relatively great width of such windows, the slats embodied in such blinds were necessarily of relatively great length and because of their thinness the slats were required to be supported by at least three, but for the most part four or more, lifting cords spaced laterally of the blind. The cord arrangements and cord lock mechanisms heretofore employed in such large blinds have been found for the most part unsatisfactory and commercially undesirable.

It has been common practice in such large blinds to secure one of the free ends of a single length of cord to the stationary support bar at the top of the blind near one side thereof from which point the cord extended downwardly through slots in the slats to the relatively thick supporting bottom slat wherein it passed around concealed and spaced pulleys and then returned upwardly through the slats to the top support bar. In the top support bar the cord passed over another pulley adjacent the center of the blind and then extended horizontally through the top of the blind to a pulley of the cord lock mechanism at one side of the blind through which it passed downwardly to form a loop. From the loop the cord was returned upwardly through the cord lock mechanism and over the same pulley thereof and then was passed horizontally to a pulley adjacent the center of the blind around which it passed downwardly to the bottom slat. In the bottom slat the cord passed around two spaced pulleys and then returned upwardly to the side of the top support bar opposite from where it started wherein the other free end of the cord was secured.

In such an arrangement, the cord was held in two places within the lock mechanism and therefore a two length cord arrangement was effected. But when one of the sections of such cord was broken due to wear or other causes with the blind in raised position, two of the cord supports

on one side or the other of the blind were destroyed, with disastrous results. The partially unsupported blind dropped downwardly on one side while being securely held on the other, causing in many instances the slats to snap and break of their own weight.

Another disadvantage of such an arrangement was that the threading of the single length of cord through the blind caused the blind to work hard and thereby increased the strain on the cord. Also, the concealed pulley arrangement in the lower slat necessitated a rather heavy slat and increased the cost thereof.

It is, therefore, an object of my invention to provide an improved cord lock mechanism and a novel lifting cord arrangement employing said cord lock mechanism.

Another object of my invention is to provide an improved multiple cord lock mechanism and a novel cord arrangement by which a plurality of cords may be held simultaneously to properly support the blind in vertically adjusted position against collapse in the event of breakage of any one of the cords at any point along its length.

25 A further object is to provide an improved cord lock device having a plurality of locking members adapted to simultaneously engage and lock a plurality of lifting cords in adjusted position, said locking members being simultaneously operable by a link mechanism by which the locking of one cord insures the locking of all cords passing through the lock device.

Other and further objects and advantages of my invention will become apparent as this description progresses, reference being had to the accompanying drawing in which,

35 Fig. 1 is a front elevational view of a Venetian blind structure embodying my improved multiple cord lock device and illustrating the novel lifting cord arrangement;

40 Fig. 2 is an enlarged front elevational view of my improved multiple cord lock device and a cord loop fastener with part of the cord broken away;

45 Fig. 3 is a vertical sectional view taken on the line 3—3 of Fig. 2 looking in the direction of the arrows;

50 Fig. 4 is a vertical sectional view taken on the line 4—4 of Fig. 3 looking in the direction of the arrows; and

55 Fig. 5 is a horizontal sectional view of the cord loop fastener taken on the line 5—5 in Fig. 3 looking in the direction of the arrows.

The Venetian blind structure shown in Fig. 1 of the drawing comprises generally an upper

stationary supporting bar 10, a tilting bar 11, a plurality of slats 12 and a bottom slat-supporting bar 13 which is adapted to support the slats thereabove when the blind is raised or lowered to vertical adjusted position. Secured to the under side of the supporting bar 10 at its left-hand end is the usual slat tilting mechanism 14, and secured to and extending through the support bar 10 at its right-hand end is my improved multiple cord lock device 15. The tilting bar 11 is supported at each of its ends for tilting movement by brackets of the tilting mechanism 14 and the cord lock mechanism 15, respectively. The slats 12 are supported by four laterally spaced ladder tapes 16 of customary form which are secured to the tilting bar 11 and extend downwardly on both front and rear sides of the slats 12 and around the slat-supporting bar 13.

The blind is provided with two lengths of cord 18 and 19, each length supporting and serving to raise or lower one-half of the blind. One of the free ends of the cord length 18 is secured at 20 to the lower slat bar 13 through which it extends upwardly in alignment with one of the ladder tapes 16 through the customary slots (not shown) in the slats 12 and through the bottom wall of the supporting bar 10 into a channel-shaped groove 21 which extends longitudinally in the upper surface of the bar 10 to the cord lock mechanism 15. Rotatably mounted within the channel-shaped groove 21 of the bar 10 and in vertical alignment with each of the ladder tapes 16 are four pulleys 22, 23, 24 and 25 over which the lengths of cord 18 and 19 are adapted to be passed.

The cord length 18, after passing into the groove 21, then passes over the pulley 22 from which it extends longitudinally within the groove 21 to the cord lock mechanism 15. Upon reaching the cord lock mechanism 15, the cord length 18 passes over and down around one groove of a two-groove pulley 26 and thence downwardly through the right-hand portion or throat 27 of the lock mechanism 15. The cord 18 then extends downwardly along the right-hand end of the slats 12 in a position accessible to the operator wherein it forms a loop and returns upwardly through the throat 27. The cord 18 then passes over and around the other groove of the pulley 26 from which it runs longitudinally within the groove 21 of the bar 10 to the pulley 23. Finally, the cord 18 passes over and around the pulley 23 and downwardly through the slats 12 and through the slat bar 13 to which its other free end is secured at 28 in laterally spaced relation with respect to the point of securing 20 of the first free end of the cord 18. The sections of the cord 18 extending between the points of securing 20 and 28 of the free ends and the cord lock mechanism 15 have been designated on the drawing as 18a and 18b, respectively.

Similarly, the free ends of the cord 19 are secured in spaced relation to the bottom slat bar 13 at 29 and 30, from which points the cord 19 passes upwardly through the slats 12 in alignment with the ladder tapes 16, through the lower wall of the support bar 10 and into the groove 21 thereof, over the pulleys 24 and 25, then longitudinally with the groove 21 to the cord lock mechanism 15 wherein it extends over a two-groove pulley 31 and downwardly through the other or left-hand throat 32 below which it is looped in substantially parallel relation to the looped end of the cord 18. The sections of the

cord 19 running between the cord lock mechanism 15 and the points of securing 29 and 30 of the free ends thereof have been designated on the drawing as 19a and 19b, respectively.

Therefore, with the foregoing arrangement, cord 18 supports the left-hand half of the blind and the cord 19 supports the right-hand half during the raising and lowering of the blind slats, with the entire blind being supported, in effect, by four lift cords 18a, 18b, 19a and 19b.

The cord lock mechanism, shown in enlarged detail in Figs. 2, 3 and 4 of the drawing, comprises a hollow casing or support member 34 having two vertical side walls 35 and 36 and a vertical end wall 38. The casing is open at the top and bottom and is divided into two vertical portions or throats 27 and 32 by a vertical inner wall or web 39 which extends between the inner faces of the vertical side walls 35 and 36. The casing 34 is also provided with a depending flange bracket 40 and a horizontally extending flange 40a by which the cord lock mechanism 15 is secured to the support bar 10, the bracket 40 also serving to support one end of the tilting bar 11.

The pulley 26 is rotatably supported in the right-hand throat 27 between the two vertical side walls 35 and 36 of the casing 34 at the extreme upper portion thereof so that the top portion of the pulley 26 extends somewhat above the top of the casing 34. Similarly, the pulley 31 is rotatably supported in the left-hand throat 32 between the two vertical side walls 35 and 36 but in a position somewhat lower than the pulley 26, the provision of different pulley heights within the casing serving to eliminate any interference between the two lengths of cords 18 and 19 during the raising and lowering operation of the blind. Each of the pulleys 26 and 31 is provided with two annular grooves within which the two sections of each of the cords 18 and 19 run.

Also mounted for pivotal movement within and at the lower portion of the throats or casing sections 27 and 32 are rockable lock members 41 and 42, respectively, which are journaled in the casing side walls 35 and 36 by pins 44 and 45, respectively. The lock members 41 and 42 are provided with depending tooth flanges 46 and 47, respectively, which are adapted to engage the two sections of each of the cords 18 and 19 and hold the same against slippage upwardly through the throats 27 and 32, the cords 18 and 19 being frictionally held between the tooth flanges 46 and 47 and projections 48 and 49 pressed out of the vertical end wall 38 and the central web 39, respectively. When the blind slats are in lowered position, each of the rockable lock members 41 and 42 assumes the position indicated by the broken lines in Fig. 4. But with the blinds in any raised position, the lock members 41 and 42 assume the position indicated by the full lines of Fig. 4.

Each of the lock members 41 and 42 are provided with pins 50 and 51, respectively, the ends of which extend through curved slots 52 and 53 in the vertical casing wall 35 and through curved slots 54 and 55 in the vertical casing wall 36. The slots 52 and 53 are in alignment with slots 54 and 55, respectively, and they are curved upwardly in an arc defined by the path of movement of the rockable members 41 and 42. The outer ends of the pins 50 and 51 which protrude through the slots 52 to 55, inclusive, and extend beyond the casing 34, are connected by

links 56 and 57. By means of the links 56 and 57, a simultaneous and unitary rocking movement of the lock members 41 and 42 is effected with the pins 51 and 52 moving in the curved slots 52, 53, 54 and 55 as the lock members 41 and 42 turn about their pivots 44 and 45.

After the blind slats have been raised to the desired level of adjustment, the sections of the cords 18 and 19 which extend below the throats 21 and 32 of the lock mechanism are moved to the left into engagement with the toothed flanges 46 and 47 of the rockable lock members 41 and 42. When this engagement has been effected, the lock members 41 and 42 will rock upwardly from their normal position to their locking position as the cords 18 are released by the operator.

The looped ends of the cords 18 which are held in fixed relative position by a fastener 60, may be grasped and manipulated as a unit by the operator. Since the two cords 18 and 19 comprise four separate sections 18a, 18b, 19a and 19b, which pass through the cord lock mechanism 15, these same cord sections, upon manipulation of the cord loops as a unit in order to secure the blind in adjusted position as above described, may sometimes fail to properly engage the teeth of either one of rockable members 41 or 42. However, because of the links 56 and 57 which effect simultaneous rocking movement and operation of lock members 41 and 42, such failure of any one of the cord lengths to engage the rockable members 41 and 42 is of no consequence since the proper engagement of only the sections of cord 18, for instance, with the lock member 41 rocks the lock member 41 into locking position with lengths of cord 18 which, in turn, by means of the links 56 and 57, causes simultaneous rocking movement of the lock member 42 from normal position to frictional locking position in locking engagement with the sections of cord 19. Thus one of the locking members may be pulled into locking engagement by the other in the event it fails to become properly engaged by the cords sought to be locked against slipping. If such simultaneous and unitary action by the lock members 41 and 42 were not present and if the operator failed to initially engage properly the toothed flanges of one of the lock members with one of the cords, the cord not so engaged would be free to slip upwardly through one of the throats to release one of the ends of the blinds, and cause damage thereto. Such inadvertent release of one of the sides of the blinds is entirely prevented by the simultaneous and unitary action of the lock members 41 and 42 by means of the links 56 and 57.

The fastener 60 comprises two oval-shaped frames 61 and 62 which are joined together and maintained in spaced relation by two threaded bolts 63 and 64. Each of the frames 61 and 62 is provided with cross bars 65 and 66, respectively, which divides each of the respective frames into two transverse slots. The two sections of each of the cords 18 and 19 pass through the slots of members 61 and 62, respectively, the four sections of the cords 18 and 19 being held thereby and capable of being operated as a unit.

With a blind of the above described construction embodying my invention, the slats are supported at four separate points by four lengths of cords 18a, 18b, 19a and 19b. These four lengths of cords are in effect four separate supporting cords since they are independent of each other between their points of securing to the bottom slat 13 and the points of engagement with the locking members 41 and 42 of the locking mech-

anism 15. In the event the left-hand cord length 18a, for instance, should break, no collapse of the heavy blind on the left-hand end would occur since the blind would still be supported partially on the left-hand side by the cord 18b which could withstand the increased load until the cord could be replaced or the blind lowered.

Although I have illustrated and described one embodiment of my invention in the foregoing drawing and specification it is to be understood that changes and modifications may be resorted to without departing from the spirit and scope of the appended claims. For instance, the cord lock mechanism may be applied to smaller blinds and used with a three cord arrangement with two cords passing down through one throat and one cord passing down through the other throat of the lock mechanism, or it may be combined with other cord arrangements.

I claim:

1. In a Venetian blind having a plurality of slats and a plurality of lift cords for raising or lowering the slats to adjusted vertical position, a cord lock device comprising a supporting body member, a plurality of rockable cord locking members pivotally supported by said body member and adapted to be rocked from inactive to cord locking position as one or more of said cords are respectively caused to engage one or more of said locking members, and a link device operably connecting said cord locking members for simultaneous and unitary rocking movement from inactive to cord locking position and return, whereby engagement of but one of said locking members with its respective cord and consequent movement of said one locking member to locking position will effect movement of the other of said locking members to locking position.

2. In a Venetian blind having a plurality of slats and a plurality of lift cords for raising or lowering the slats to adjusted vertical position, a cord lock device comprising a supporting body member, a plurality of movable cord locking members movably supported by said body member and adapted to be moved from inactive to cord locking position as one or more of said cords are respectively caused to engage one or more of said locking members, and a link device operably connecting said cord locking members for simultaneous and unitary movement from inactive to cord locking position and return, whereby engagement of but one of said locking members with its respective cord and consequent movement of said one locking member to locking position will effect movement of the other of said locking members to locking position.

3. In a Venetian blind having a plurality of slats and a plurality of lift cords for raising or lowering the slats to adjusted vertical position, a cord lock device comprising a supporting body member, said body member being divided into a plurality of throats through which the plurality of lift cords respectively extend, a pulley in the upper portion of each throat over which the respective lift cords are operatively engaged, said pulleys being arranged in tandem with their axes of rotation in parallel relationship, a plurality of rockable cord locking members, one in each throat pivotally supported by said body member and adapted to be rocked from inactive to cord locking position as one or more of said cords are respectively caused to engage one or more of said locking members, and a link device operably connecting said rockable cord locking members for simultaneous and unitary rocking movement

from inactive to cord locking position and return, whereby engagement of but one of said locking members with its respective cord and consequent movement of said one locking member to locking position will effect movement of the other of said locking members to locking position.

4. In a Venetian blind having a plurality of slats and a plurality of lift cords for raising or lowering the slats to adjusted vertical position, a cord lock device comprising a supporting body member having two side walls and being divided into a plurality of throats through which the lift cords are passed, a plurality of rockable cord locking members, one in each throat, pivotally supported by said side walls and adapted to be rocked from inactive to cord locking position, at least one of said side walls having a plurality of curved slots, one adjacent each rockable member, and said slots being curved in the direction of rocking movement of said rockable members, a pin carried by each rockable cord locking member and extending through the adjacent curved slot, and a link mounted on and connecting the outer ends of said pins for effecting simultaneous and unitary rocking movement of said rockable members from inactive to cord locking position and return.

5. In a Venetian blind having a plurality of slats and a plurality of lift cords for raising or lowering the slats to adjusted position, a cord lock device comprising a supporting body member having two side walls and at least one partition wall connecting and extending between said side walls intermediate their edges and dividing said body member into a plurality of throats through which the lift cords are passed, a plurality of rockable cord locking members, one in each throat, pivotally supported by and within said side walls and adapted to be rocked from inactive to cord locking position, each of said side walls being provided with a plurality of

curved slots adjacent the rockable members and the slots of one side wall being in alignment with the slots on the other side wall, pins mounted on each side of said rockable cord locking members and extending through the adjacent curved slots in said side walls, and links mounted on and connecting the outer ends of said pins on the exterior of said side walls for effecting simultaneous and unitary rocking movement of said rockable members from inactive to cord locking position and return.

6. A Venetian blind comprising a plurality of slats, a plurality of spaced ladder tapes for supporting said slats, three or more spaced lift cords adapted to raise or lower the slats to adjusted position and to support one or more slats when in raised position, a cord lock device for adjustably securing each of said cords in adjusted vertical position, said lift cords being secured in spaced relation along and to the lowermost slat and extending upwardly through said slats to the top of said blind and thence through said cork lock device and said lift cords, after passing through said lock device, being secured together and adapted to be grasped as a unit by the operator for raising and lowering the slats in horizontal, parallel position relative to each other, and said cord lock device comprising a supporting body member, a plurality of movable cord locking members pivotally supported by said body member and adapted to be moved from inactive to cord locking position to lock respectively said cords in raised position, and a link device connecting said cord locking members for simultaneous and unitary movement from inactive to cord locking position and return, whereby each cord is caused to be engaged and locked by its respective locking member and the blind is properly supported against sudden release by at least two spaced cords in the event of breakage of any one of said three or more cords.

EDWARD E. SCHAEFER.
